PORTABLE TYPEWRITER

Marcel Fresard, Geneva, Switzerland, assignor to Mefina S.A., Fribourg, Switzerland, a corporation of Switzerland

Filed Feb. 20, 1959, Ser. No. 794,623

Claims priority, application Switzerland Mar. 7, 1958

15 Claims. (Cl. 197—186)

My invention has for its object a portable typewriter including a frame carrying a cradle over which may slide the carriage carrying the platen-roller of the typewriter, said frame carrying a guide segment to which are pivotally secured the type bars which are connected each through a rod with a rocking lever actuated in its turn by a corresponding key bar.

Various embodiments of such portable typewriters are known. However, they have a comparatively large bulk, which prevents for instance introducing such a typewriter inside a document case.

On the other hand, office typewriters are known the keyboard of which may be folded through about 90° into its inoperative position through engagement with the central section of the chassis. Such a structure allows reducing somewhat the total bulk of the machine, so that it may be capped for instance by a bell-shaped protecting case.

My invention has for its object the production of a portable typewriter provided with a conventional keyboard, the bulk of which is substantially of the same magnitude as that of the conventional portable typewriter, when the machine is operative, while the bulk of said machine may be considerably reduced, when it is set in its packaged condition, which allows its easy transportation.

My improved portable typewriter is characterized by the fact that the rocking levers and the key-carrying bars are pivotally secured to a common shaft extending transversely of the machine, each key bar acting on the corresponding rocking lever through the agency of a pusher cam pivotally secured to an axis parallel to said common shaft. Said arrangement allows folding the machine when it is desired to set it in its packaged condition under minimum bulk conditions, as provided by a pivotal movement of the key bars through an angle of about 180° round said common shaft and by a collapsing of the rocking levers and of the type bars within the frame, between the guide segment and the common shaft.

Accompanying drawings illustrate diagrammatically and by way of example a preferred embodiment of my improved portable typewriter. In said drawings:

FIG. 1 is a longitudinal partly sectional view of the machine showing its various parts.

FIG. 2 is a side view showing the machine in its folded packaged condition.

FIG. 3 illustrates on a larger scale and partly sectionally the rear half of the typewriter frame.

FIG. 4 shows similarly on a larger scale and partly sectionally the front half of the typewriter frame.

FIG. 5 is a view of the typewriter frame from above.

FIG. 6 is a view of the keyboard from above.

FIG. 7 is a lateral elevational view of the typewriter in its packaged condition, said view being partly broken

2

away so as to show the position occupied by the main parts.

Turning to FIGS. 1, 3 and 4, my improved portable typewriter includes a casing incorporating a frame 1 carrying a cradle 2 which slidably receives the carriage 3 which in turn supports the platen roller 4. The cradle 2 is pivotally secured to a spindle 5 arranged transversely inside the frame 1. This manner of mounting the cradle 2 allows it to be rocked transversely under the action of a motion mechanism of any suitable type. Said transverse rocking movement of the cradle 2 serves when it is desired to pass from typing with lower case small letters to typing with upper case capital letters; said cradle carries rails 6 constituted by angle bars and over which the carriage 3 is guided with the interposition of rollers 7 between said rails 6 and angle bars 8 forming part of the carriage 3. Said carriage 3 is continuously subjected to the tractive action of a spring-drum 9 (FIG. 5); the carriage 3 is held in position by means of an escapement mechanism designated as a whole by the reference number 10 (FIG. 3). In the embodiment described, the escapement mechanism 10 is stationary with reference to the frame 1 and it is shown as secured to the cross member 11 of the frame carrying the type-carrying bars 12.

25 of the typewriter.

A lever 13 is pivotally secured at 14 to each end of the carriage 3. These levers 13 carry each at one end a rack 15 meshing with a pinion 16 forming part of the escapement mechanism 10. A spring 17 urges the rack 15 into engagement with the corresponding pinion 16 notwithstanding the transverse movement imparted to the carriage 3 by the escapement mechanism.

The type-carrying bars 12 which are pivotally secured at 18 to the cross member 11 are connected each through 30 a link 19 with a rocking lever 20 (FIG. 1). The different rocking levers 20 are carried by a cross-member 21 forming part of the frame 1 and in which are provided a series of slots 22 (FIGS. 4 and 6). Each slot 22 has a breadth sufficient for it to receive not only a rocking lever 20, but also the end of a corresponding key-carrying bar 23. The system of rocking levers 20 and of key-carrying bars 23 is pivotally secured to a common shaft 24 arranged transversely of the typewriter. Each key-carrying bar 23 acts on the corresponding rocking lever 20 through the agency of a pusher cam 25. The different pusher cams 25 are arranged in the lower portion of the corresponding slots 22 and are all pivotally secured to the same spindle 26 engaging the frame 1 and arranged in parallelism with and underneath the common shaft 24. A rod 27 parallel with the spindle 26 is carried by two arms 28 pivotally secured to the spindle 26 and extending inside two slots 22 located in proximity to the lateral edges of the frame 1. These arms 28 are engaged at their ends 29 by corresponding springs 30, the other ends of which are secured at 31 to the frame 1. The rod 27 engaging said arms 28 is thus subjected to a transverse elastic action which is transmitted through contact to the entire series of pusher cams 25. Said rod 27 defines 45 thus the inoperative positions of the pusher cams 25 which are exactly the same for the whole series of cams. The contacting point of the actuating nose 32 of the key-carrying bars 23 with the adjacent edge of a pusher cam 25 is selected as a function of the distance separating the 50 key 33 from the common shaft 24, so that the operative

55 ends of the arms 28 are secured at 31 to the frame 1. The rod 27 engaging said arms 28 is thus subjected to a transverse elastic action which is transmitted through contact to the entire series of pusher cams 25. Said rod 27 defines 60 thus the inoperative positions of the pusher cams 25 which are exactly the same for the whole series of cams. The contacting point of the actuating nose 32 of the key-carrying bars 23 with the adjacent edge of a pusher cam 25 is selected as a function of the distance separating the 65 key 33 from the common shaft 24, so that the operative

travel may be equal for all the keys 33. Thus, the contact point 32 corresponding to a key 33 located near the common shaft 24 will be provided at a level higher on the cam 25 than the contact point 32' corresponding to a key 33 located at a greater distance from the common shaft 24, such as a key on the lower row of the keyboard. In contradistinction, the contact points of the actuating edge 34 of the rocking levers 20 and the related edge of the pusher cams 25 corresponding thereto are all provided at the same level.

Obviously, and in accordance with a modification, it is possible to obtain a uniform operative travel for the different keys 33 by positioning the different contact points 32 at the same level, in which case the contact points 34 should be located at levels defined as functions of the distances between the keys 33 and the common shaft 24. It should be remarked that the opening 35 provided in each lever 20 to provide for the pivotal connection with the corresponding link 19 is elongated, so as to allow a transverse shifting of the corresponding pivotal axis and to further, as will be explained herein-after, the collapsing of the type-carrying bars 12 and of the locking levers 20. According to a modification, it is obviously possible to provide openings 35 of the usual circular shape in which case the openings 36 through which the rods 19 are secured to the corresponding type-carrying bars 12 are given an elongated shape so as to allow a transverse shifting of said pivotal axis.

The typewriter illustrated includes a lifting bridge 37 and a lowering bridge 38 for the system of rocking levers 20. Said bridges are connected with said common shaft 24 through the agency of corresponding flanges 39 and 40 engaging slots 22 formed in the cross-member 21 of the frame 1 in proximity with the ends of the latter. The raising bridge 37 passes thus underneath the arrangement constituted by the rocking levers 20 while the lowering bridge 38 extends above said levers 20. Said raising bridge 37 carries furthermore a member 41 adapted to form an abutment stopping the type-carrying bars 12 when in their operative position. Said abutment 41 is rigidly secured to said raising bridge 37 and cooperates with the latter with a view to setting the type-carrying bars in their operative positions together with the rocking levers 20 when the typewriter is open for operation.

The typewriter includes furthermore a protecting plate 42 extending above the lowering bridge 38 and pivotally secured along an axis 43 lying in parallelism with the common shaft 24 and near the latter.

As a matter of fact, in FIG. 4 it will be seen that said protecting plate 42 is pivotally secured through rivets 44 to two arms 45 which are pivotally secured in their turn to said common shaft 24. The outer ends 46 of said arms 45 slide inside the sideways 47 provided along the opposite lateral edges of a casing cover 48. Said cover 48 forms part of the general casing adapted to enclose the typewriter for transportation. This cover 48 is pivotally secured to the frame 1 through one of its edges along the axis 49 parallel with the common shaft 24 and lying underneath the latter.

In the embodiment illustrated, said axis 49 is constituted by two trunnions, while the cover is adapted, on the one hand, to close the typewriter and to extend over the upper section of the latter in its packaged condition and, on the other hand, to form an extension of the frame 1 so as to lie underneath the key-carrying bars 23 when the typewriter is in its operative condition. For this operative condition of the typewriter, the cover 48 forms also a section of the support of the typewriter.

As will appear from FIG. 4, the section 50 of the casing cover 48 located in proximity with the pivotal axis 49 is pivotally secured its turn at 51 with the body of the cover 48. Said section 50 is adapted to form means for locking said cover 48 in the open operative condition of the typewriter. To this end, it is provided with projecting claws 52 which are adapted to engage the edge

53 of the frame 1. This position securing the side 50 is obtained through the action of the clamping spring 54 engaging the pivotal axis 51 and urging the section 50 against the body of the cover 48.

Referring to FIGS. 1 and 2, it will be seen that the casing of the typewriter includes furthermore a section 55 adapted to enclose, for the packaged condition of the typewriter, the portion of the frame 1 of the typewriter including the lower part thereof and the part located to the rear of the platen-roller 4 and the ends of the latter.

Said casing section 55 is pivotally secured at 56 through two flanges 57 to the underside of the frame 1. Thus, in its open position facing downwardly, said section 55 forms also a part of the support provided for the typewriter. It should be remarked that said casing section 55 is made of two parts which are pivotally interconnected by the spindle 58, the auxiliary part 59 being adapted to close the casing of the typewriter to the rear of the platen-roller 4. Said auxiliary part 59 carries securing means 60 adapted to cooperate with a notch 61 provided in the front edge of the cover 48 (FIG. 2). Said securing means 60 are carried elastically by the auxiliary part 59 so that it is sufficient to depress the push member 62 to thereby release the securing means 60 with reference to the notch 61 and thus disengage the cover 48 of the casing. The casing of the typewriter includes also the two flanges 63 adapted to cover the sides of the frame 1 and a bottom 64 adapted to close the underside of said frame.

The arms 45, the ends 46 of which slide in the sideways 47 formed in the sidewalls of the cover 48, carry each an abutment 65 adapted to engage upon opening of the cover 48 the raising bridge 37, so as to produce a rising movement of the latter and, consequently, the positioning in the position corresponding to operation of the typewriter, of the type-carrying bars 12 and of the rocking levers 20. Said abutments 65 act on the edges 66 of the corresponding flanges 39 (FIGS. 1 and 6).

Means are provided for controlling the movements of the protecting plate 42 during the opening and the closing of the machine. Said means include a cam 67 rigid with the flanges 40 of the lowering bridge 38 and the outline of which engages the edge 68 of the protecting plate 42. The typewriter includes furthermore a member for releasing the cover 48, which member is constituted by a plate 69 pivotally secured to the frame 1 along an axis 70 parallel with the common shaft 24 (FIG. 4). Said plate 69 is provided with a slot 71 in the shape of an arc of a circle the radius of which is larger than the distance separating said slot 71 from the pivotal axis 70. The center of curvature of said arcuate slot 71 is shown at 72 in FIG. 4. Said slot 71 extends furthermore at its upper end into a slot section 73 on the outside of the arc of a circle referred to. A pin 74 rigid with the lowering bridge 38 engages said slot 71. The whole arrangement is designed in a manner such that said pin 74 engages the extension 73 of the slot 71, when the typewriter is in its operative condition. Any pressure exerted downwardly on the lowering bridge 38 and more particularly on the lugs 75 carried by the flanges 40 of said lowering bridge will lead to a downward shifting through the agency of said pin 74 of the releasing plate 69 up to a point at which the heel-shaped projection 76 of said plate 69 impinges against the abutments 77 secured inside the cover section 50, said abutments 77 passing through openings 78 in the bottom 64 of the general casing. At the moment at which the projection 76 reaches the level defined by said bottom 64, the arcuate path followed by the pin 74 and the center of which lies on the common shaft 24 registers with the arcuate line defining the slot 71. Consequently, the pin 74 is no longer within the extension 73 of the slot 71 and enters the main section of the latter. Thus, the complete lowering stroke of the lowering bridge 38 providing for the collapse of the rocking levers 20 and of

70

the type-carrying bars 12 may continue, notwithstanding the locking of the releasing plate 69 in contact with the bottom 64 by the shifting of the pin 74 inside the arcuate section of the slot 71 (FIG. 4).

The escapement bridge 79 (FIG. 4) on the typewriter is pivotally connected through lugs 80 with the common shaft 24 to which are pivotally secured the key-carrying bars and the rocking levers 20. The escapement bridge 79 is consequently raised each time a type is depressed, through the corresponding rocking lever 20. Said escapement bridge carries in its central section a member 81 to which is pivotally secured at 82 a rod 83 one end 84 of which is offset and of substantially hook-like formation (FIG. 3) so as to control in the conventional manner the escapement mechanism 10 for the typewriter and thereby the axial movements of the carriage 3 carrying the platen-roller 4.

The carriage 3 is provided furthermore with a line space adjusting mechanism 85 of a conventional structure (FIG. 3). However, the control lever generally used for such a mechanism has been omitted and replaced by a push member 86 with a view to reducing the bulk of the member controlling the line space adjusting mechanism.

If it is desired to set in its operative position the above-described typewriter when it is in its packaged condition of a reduced bulk as illustrated in FIG. 2, the push member 62 should first be depressed, so as to release the cover 48 and to make the latter pivot through 180° round its pivotal axis 49. During this pivotal movement of the cover 48, the arms 45 are driven into regular motion by the slideways 47. This returns the pivotal axis 43 of the protecting plate 42 into registry with the front of the common shaft 24. Consequently, the edge 87 of the protecting plate 42 causes the key-carrying bars 23 to rock and to enter their operative positions. The first portion of the angular shifting through 180° of the key-carrying bars 23 is thus produced by said thrust exerted by the edge 87 on said bars 23, the remainder of the angular shifting of the bars 23 being obtained under the action of gravity.

During said opening movement of the cover 48, its section 50 moves aside and revolves round the axis 51, so that the claws 52 on said section slide over the bottom 64 and engage the edge 53 of the frame under the action of springs 54 which urge the section 50 against the bottom 64, while the stops 65 act on the flanges 39 of the raising bridge 37 through their edges 66. Thus, the type-carrying bars 12 are raised by the abutment member 41 so as to be brought into their operative positions, the rocking levers 20 being set in their operative positions by the raising bridge 37. Simultaneously with said rising movement of the raising bridge 37, the lowering bridge 38 is raised so that the cam 67 which is rigid therewith produces in its turn a raising of the protecting plate 42 which frees the space above the type-carrying bars 12 during their movement leading them into their operative positions. The rising movement of the lowering bridge 38 leads to the drive through the pin 74 of the releasing plate 69. After turning the casing section 55 upside down, so as to make it form a part of the support for the typewriter, the latter is ready for use in its operative position. The raising and lowering bridges 37 and 38 are held in their operative positions at a sufficient distance from the rocking levers 20, so that during the typing said levers cannot engage said bridges 37 and 38. The abutment 41 carries a sheath 88 adapted to absorb the shocks of the type-carrying bars 12 during their return movement towards said abutment 41.

The operation of such a typewriter when in its operative position is quite similar to that of conventional portable typewriters. It should be remarked that the keyboard formed by the keys 33 of the typewriter is of the usual stepped formation and has the size of a conventional typewriter keyboard (FIGS. 1 and 6).

When it is desired to pack up the machine so as to bring

it into its position of minimum bulk, the carriage 3 is first brought into its central position with reference to the frame 1 after which a downwardly directed pressure is exerted on the lugs 75 of the flanges 40 of the lowering bridge 38. This leads to a collapse of the rocking levers 20, of the raising bridge 37 and of the abutment 41, which releases in its turn the type-carrying bars 12 which collapse together with the rocking levers 20 between the segment 11 of the typewriter and the common shaft 24. During the lowering movement of the bridge 38, the heel 76 on the releasing plate 69 engages the abutments 77 which release the section 50 of the cover 48. The latter may therefore be rocked through 180°; the corresponding movement of the arms 45 allows a dropping of the protecting plate 42 on to the central part of the frame 1, the key-carrying bars 23 being folded back over said protecting plate 42 at about 180° from their operative position (FIG. 7). It is then sufficient to turn the casing section 55 upside down so that it may cover the part of the frame located underneath and behind the carriage 3. The cover 48 of the casing may then be folded entirely over the typewriter until the securing means 60 enter the notch 61 in said cover so as to hold the typewriter casing in its closed position, as illustrated in FIG. 2.

The preceding disclosure and accompanying drawings show that the bulk of the packaged typewriter is smaller than one half of the bulk of the typewriter in its operative condition. It may be mentioned by way of information that one typewriter executed in the manner described and illustrated has, when packaged, the shape of a parallelopipedic box, the outer size of which is 250 x 143 x 31.5 mm. With such a small volume, said typewriter may be readily carried inside a document case for instance or even inside a coat pocket. It should be remarked, as concerns the numerical example which has just been given, that in spite of the height of 31.5 mm. of the machine in its packaged condition, the diameter of the platen-roller of the latter may be equal to 25 mm. which is a very conventional platen-roller size for portable typewriters.

I claim:

1. In a portable collapsible typewriter, the combination comprising a frame including a first cross member and a second cross member, a cradle pivoted transversely of the frame and selectively movable from a normal lowered position to an upper position, an escapement controlled platen supporting carriage slidably mounted in the cradle, a series of type bars pivotally supported on the first cross member of the frame, a series of rocking levers each related to one of the type bars and each having an opening near one end and an actuating edge near the other end, a link connecting the end of each type bar opposite its type face with the opening in the free end of a related rocking lever, key bars separate from said rocking levers and each having an actuating nose, a shaft disposed transversely of said second cross member and providing a common axis for all juxtaposed rocking levers and key bars to support said levers and bars in operative or collapsed condition, a series of cams normally disposed between the said actuating edges of the rocking levers and the noses of the key bars to couple said levers and bars in operative relation, a spindle extending transversely of the frame and arranged parallel to and at one side of the shaft, said spindle coaxially supporting all of the cams, and means spring-biasing said cams to operative position between the said edges of the rocking levers and the noses of the key bars, whereby depressing a key bar will actuate a related type bar through the pusher cam upon pivotal movement of the key bar when the typewriter is in use, and when the typewriter is to be collapsed, the said actuating edges of the rocking levers will move the related pusher cams against the force of said spring-biasing means to a downward position and clear of the said actuating noses of the said key bars.
2. A typewriter as claimed in claim 1, wherein the opening in each rocking lever which receives one end of the link, has an elongated shape to provide transverse

shifting of the corresponding pivotal axis and to further assist the collapsing of the type bars and of the rocking levers.

3. A typewriter as claimed in claim 1, including a raising bridge and a lowering bridge for the system of rocking levers, said bridges being pivotally mounted on said shaft, and the raising bridge extending underneath the rocking levers and the lowering bridge extending over the said levers, a member on the raising bridge forming a stop for the return movement of the type bars in their operative positions, said stop cooperating with the said raising bridge for urging the type bars and the rocking levers into their operative positions when the machine is being set in its open operative position, a protecting plate disposed above the lowering bridge and pivotally secured along an axis parallel with the shaft and lying in proximity to the latter, and means controlling the raising and lowering movements of said protecting plate respectively during collapsing and setting up the type bars into their inoperative or operative positions.

4. In a portable collapsible typewriter, the combination comprising a casing, including a top wall constituting a cover, a bottom wall, side walls and opposite end walls, said end walls respectively pivotally connected with said bottom wall and with the cover and having opening movement to set up the typewriter for use and closing movement when the typewriter is collapsed for storage, a frame on the bottom wall of the casing, a platen supporting carriage on the frame, a plurality of type bars coaxially pivoted on the frame, a shaft supported transversely of the frame, a plurality of rocker levers mounted on said shaft and connected at one end to the type bars at the end opposite the type face, a plurality of key bars also mounted coaxially on said shaft with the rocker levers, coupling means normally spring biased to a position between the rocker levers and key bars at one side of their axes to place them in operative relation when the casing is open, and means on said rocker levers for moving said coupling means to an inoperative position when it is desired to collapse the casing by moving the cover and all of the key bars through an angle of 180° to overlie the rocker levers.

5. A portable collapsible typewriter as set forth in claim 4, wherein the end walls are integrally connected at substantially right angles respectively with one edge of the cover and with one edge of the bottom wall and the other free edges of the end walls are pivotally connected respectively to the cover and the bottom wall, and latch means for connecting the free edge of the integral end wall of the cover with the pivoted end wall of the bottom plate.

6. A portable collapsible typewriter as set forth in claim 4, wherein a lifting bridge and a lowering bridge are disposed respectively below and above the rocker levers, and said bridges have arms pivotally mounted on the shaft which supports the rocker levers and the key bars.

7. A portable collapsible typewriter as set forth in claim 4, wherein a protecting plate overlies the position of the rocker levers and is pivotally connected with links having rollers operating in guides on the cover.

8. A portable collapsible typewriter as claimed in claim 4, wherein the cover of the casing is pivotally connected to the frame along one of its edges about an axis parallel with the shaft and arranged beneath the latter, said cover adapted to close the upper part of the typewriter when in its packaged condition, and also to form an extension of the frame underneath the key bars and simultaneously constitute a part of the support for the typewriter in its operative condition.

9. A portable collapsible typewriter as claimed in claim 4, wherein the cover of the casing is pivotally connected to the frame along one of its edges about an axis parallel with the shaft and arranged beneath the latter, said cover adapted to close the upper part of the typewriter when in its packaged condition, and also to form an extension

of the frame underneath the key bars and simultaneously constitute a part of the support for the typewriter in its operative condition, and wherein when the end wall of the cover lying nearest its pivotal connection with the frame is in its reversed operative position it supports the typewriter through engagement with the frame.

10. A portable collapsible typewriter as claimed in claim 4, wherein the casing includes an end wall pivotally secured through two lateral flanges to the frame so that when the typewriter is in its open operative position, said casing section is turned upside down to form the support for the platen end of the typewriter.

11. A portable collapsible typewriter as claimed in claim 4, including lifting and lowering bridges pivoted on said shaft, a protecting plate overlying the rocker levers, arms also pivotally secured to the shaft and pivotally connected to the protecting plate, and means controlling the movements of said plate including at least one cam rigid with the lowering bridge, the periphery of said cam 20 engaging said protecting plate.

12. A portable collapsible typewriter as claimed in claim 4, including a lifting bridge disposed below the rocker levers, a lowering bridge arranged above said rocker levers, a releasing plate pivotally secured to the frame 25 along an axis parallel with the said shaft, said plate which releases the cover of the casing being provided with a slot extending over the arc of a circle, the radius of which is larger than the distance separating said slot from the pivotal axis of said plate, said slot including an upper extension on the outside of said arc of a circle, and a pin 30 rigid with said lowering bridge engaging in said slot, so as to lie in the extension of the slot when the typewriter is in its operative condition, whereby any pressure exerted downwardly on the lowering bridge will produce a downward movement of the releasing plate until the lower end of the latter urges the pivoted section of the cover into its released position, the complete lowering of the lowering bridge for collapsing the rocker levers and the type bars continuing notwithstanding the locking of the releasing plate upon the pin shifting inside the main arcuate 35 section of the slot in said releasing plate.

13. A portable collapsible typewriter as set forth in claim 4, wherein the platen supporting carriage includes a cradle slidable in the casing frame and the said platen may be manually raised and lowered when it is desired 45 to type capital letters or with small letters, a rack on the carriage meshing with a pinion forming part of an escapement mechanism for producing axial movement of the carriage under the control of an escapement bridge after impact of each type, said escapement mechanism being stationary with reference to the frame, and spring means for urging the rack into permanent mesh with said pinion.

14. A portable collapsible typewriter as set forth in claim 13, wherein the escapement bridge is pivotally secured to said shaft which mounts the key bars and the rocker levers.

15. In a portable collapsible typewriter, the combination comprising a casing, including a top wall constituting a cover, a bottom wall, side walls and opposite end walls, said end walls respectively pivotally connected with said bottom wall and with the cover and having opening movement to set up the typewriter for use and closing movement when the typewriter is collapsed for storage, a frame on the bottom wall of the casing, a platen supporting carriage on the frame, a plurality of type bars coaxially pivoted on the frame, a shaft supported transversely of the frame, a plurality of rocker levers mounted on said shaft and connected at one end to the type bars at the end opposite the type face, a plurality of key bars also mounted coaxially on said shaft with the rocker levers, coupling means normally spring biased to a position between the rocker levers and key bars at one side of their axes to place them in operative relation when the casing is open, a lifting bridge and a lowering bridge dis-

posed respectively below and above the rocker levers, said bridges having flanges pivotally mounted on said shaft which supports the rocker levers and key bars, arms pivotally mounted on the said shaft, guides located along the opposite lateral edges of said cover and slidably receiving the ends of said arms opposite those pivotally mounted on said shaft, and means on said arms to act on the flanges of the lifting bridge during the opening of the cover to urge the lifting bridge upwardly to set

the type bars and the rocker levers in their operative positions.
